UNITED STATES PATENT OFFICE

HENRY OTTO GRAU, OF CHEVIOT, OHIO

PLAYER-PIANO MECHANISM

Application filed April 5, 1926. Serial No. 99,864.

My invention relates to pneumatically operated mechanisms that function to actuate the hammers of a piano, chimes, xylophone, or other musical instrument having a striking mechanism.

Such striker actuating mechanism may also be used to operate the sustaining mechanism, loud and soft mechanisms, and to operate the tone shading portion of the reproducing mechanism. The mechanism is adapted to be built into the case with the musical instrument.

The principal object of my invention is to provide sturdy, durable and sensitive pneumatic means for actuating the hammers. To those ends my invention comprises novel means for directing the flow of air thru passages communicating with chambers having diaphragms, means for bleeding certain of said passages, and means for enclosing and for protecting said diaphragms.

Another object of my invention is to eliminate the bellows heretofore used for each note producing unit and instead of such former combination to provide a self-contained actuating unit mechanism. In player mechanisms now in use, the chamois, kid or other leather used in the bellows is exposed to dust and dirt and in contact with freely circulating air, so that it becomes hard and brittle, requiring renewal frequently and this involves great trouble and expense.

Another object of my invention is to provide a complete and separate striker unit assembly adapted to function to produce one note, which assembly may be removed from a completely assembled player action without disturbing any of the other units or their connections.

Another object of my invention is to provide a player piano action suitable for use in either a grand or upright piano.

Another object of my invention is to provide means for limiting the stroke of the striking rocker arm and means to compensate for wear of the felt.

Another object of my invention is to provide means for readily replacing the bleeder tubes with those of different sized orifice.

Another object of my invention is to pro-

vide external air to the interior of the striker or actuating unit directly through the casting, thus shortening the path of its travel to the power side of the actuating diaphragm, reducing friction and therefore increasing the efficiency of the unit.

In the particular embodiment of my invention selected for illustration,

Figure 1, is a vertical section from front to back thru an upright player piano, showing the complete action in side elevation,

Fig. 2, an enlarged detail, is a side elevation of one player striking unit and connections mounted on the main channel shown in cross section; the unit's internal mechanism chambers and passages being shown in dotted lines; and a portion of the tube leading to the tracker bar being broken away,

Fig. 3, an enlarged detail, is a front elevation, of four striking units, the contiguous passages shown in dotted lines, mounted on a piece of the main channel,

Fig. 4, an enlarged detail, is a side elevation of the block which forms the casing of the striking unit, with the internal chambers and passages shown in dotted lines,

Fig. 5, is a top plan view of the same,

Fig. 6, is a cross section on the line 8—8 of Fig. 4,

Fig. 7, is a cross section on the line 9—9 of Fig. 4, offset as indicated on Fig. 5 by line 9—9.

Fig. 8, is a cross section on the line 10—10 of Fig. 4,

Fig. 9, an enlarged detail, is an elevation of the double valve for both intake and exhaust, with part of the stem broken away,

Fig. 10, an enlarged detail, is an elevation of the plunger and its guide valve, with part of the stem broken away,

Fig. 11, is a top plan view of Fig. 10.

Fig. 12, is a side elevation of the bleed tube, with part broken away,

Fig. 13, a detail is a top plan view of the same,

Fig. 14, a detail, is a cartridge-shell-shaped bleed, with part of the stem broken away,

Fig. 15, is a top plan view of the valve pouch block,

Fig. 16, is a vertical section on the line 18—18 of Fig. 15,

Fig. 17, a detail, is an adjustable stop for striking rocker arm to correct for wear of the felt cushioning,

Fig. 18, is a top plan view of the block which forms the casing for plunger valve, with the passages shown in dotted lines, and

Fig. 19, is a vertical section on the line 21—21 of Fig. 18.

Referring now to the drawings, C is the usual upright piano case within which is mounted the complete piano action B, and the player action consisting of an upper portion A and a lower portion D.

Each or each group of the harp strings b are adapted to be struck by a hammer b¹ actuated by manually striking the keys b² or through mechanical means constituting the player action hereinafter described.

The lower portion of the player action consists of foot power actuated bellows d¹ and adapted to be operated by treadle d operatively secured to the lower end of the vacuum tube d². The tube d² is connected at its upper end to the main channels d³, d⁴ placed the latter above the former and extending in a horizontal direction within the case substantially parallel with the key-board.

Mounted upon and positioned across each of the main channels are an appropriate number for any given scale of striking units a. These units are identical in every particular excepting as to the length and shape of the striking rocker arm which is altered to adapt it for proper contact with certain of the hammers.

The main casing a¹ has two connected chambers a³² above and a³³ below separated by a main power diaphragm a⁵ of soft leather or other suitable material. Upon this diaphragm rests the button of a strike plunger a⁴, while its stem extends upward vertically thru the strike plunger valve casing a² terminating outside the unit just below a cushion a²⁴ of felt or buckskin on the underside of a stop a⁸ secured to the striking rocker arm a¹⁰ and adjustable with relation thereto by means of the screw a⁹.

The strike plunger valve casing member a² is secured to the main casing a¹ by means of screws a²² with a piece of buckskin or other suitable packing material a²⁶ between said members to ensure a sealing fit. A chamber a³⁴ is formed in the top of the member a² and this chamber is closed at the top by a diaphragm of leather or other suitable material a²⁰, to the under side of which is secured a strike plunger guide valve a⁶ provided with vertical holes a³⁵ in which are vertically positioned guide pins a⁷ fixed in the bottom wall of the chamber a³⁴, and a³⁰ is the leather packing for strike plunger guide valve a⁶.

Screws a²¹ pass thru the elements a² and a¹ and secure the unit a to the main channel

board d³ with leather or other suitable packing a²⁷ between and d³ has air passage d⁵ closed at the bottom by packing d⁶ and channel board d⁷. A supporting post a¹¹ is secured to the member a² by screws a²³ and supports the striking rocker arm a¹⁰ pivoted to it by the bushed pin a¹². The felt, buckskin or otherwise cushioned end a⁵¹ of the striking rocker arm a¹⁰ is adapted to actuate a hammer b¹. The movement of the arm a¹⁰ may be limited by the adjustable screw a¹⁴ and its check button a¹³ which has felt or other pad a²⁵.

The tracker bar T is connected by the tube t to an adjustable bleeder tube a¹⁸, the other end of which enters the chamber a³⁶ formed in the upper side of the pouch block a³. The block a³ fits into a notched out portion on the under side of the main casing a¹, is secured in position by screws a³⁷ and its chamber a³⁶ registers with a corresponding chamber a³⁸ in the main casing a¹ and is separated therefrom by the diaphragm a¹⁵ of leather or other suitable material.

A double valve whose lower button a¹⁶ has a cushion a²⁹ of leather or other suitable material on its top surface has a stem to the upper end of which is secured the disc valve a¹⁷ with cushion a²⁸ on its under surface.

The bleed tube a¹⁸ connects the tracker bar tube t with the chamber a³⁶. The port a³⁹ in bleed tube a¹⁸ connects with the passage a⁴⁰ in the main casing a¹ and this passage a⁴⁰ connects with the chamber a³⁸. The chamber a³⁸ is connected by the passage a⁴¹ with a vertical passage a⁴² leading from the chamber a³ and an oblique passage a⁴³ connecting with the chamber a³².

A cartridge shaped bleeder tube a¹⁰ closes the outer end of the passage a⁴⁴ which leads to the chamber a³³. Passage a⁵³ is connected by the vertical passage a⁴⁵ with the horizontal passage a⁴⁶ in the strike plunger valve casing member a², which connects with the chamber a³⁴. Passage a⁴⁵ is connected by passage a⁴⁷ with passages a⁴⁸, a⁴⁹ and a⁵⁰, which terminate on the upper surface of casing member a¹ under leather a²⁸ of valve disc a¹⁷.

The operation is as follows:

The music roll sheet passes forward over the face of the tracker bar T. When one of the perforations in the music sheet passes over the end of the duct in the tracker bar thru which the particular unit action is controlled, the vacuum is broken, air rushes in thru the duct in the tracker bar thru tube t, bleeder tube a¹⁸ into chamber a³⁶ and this forces upward the diaphragm a¹⁵ and the button a¹⁶ carrying its stem and the valve a¹⁷ upwardly opening the passages a⁴⁸, a⁴⁹, a⁵⁰ to atmosphere. The air rushes in downwardly thru these passages to the passage a⁴⁷ horizontally thru said passage, and upwardly and downwardly thru a⁴⁵ and horizontally thru a⁴⁶ to chamber a³⁴ and hori-

zontally thru a^{53} to chamber a^{33} ; the dia-
phragm a^5 is forced upwardly carrying but-
ton a^4 and its stem upwardly. The air ad-
mitted to chamber a^{34} balances pressures
above and below the diaphragm a^{20} , overcom-
ing any opposing pressure differential on this
diaphragm, and the action of the diaphragm
 a^5 forces the top of the stem against the
cushion a^{24} , and raises the striking rocker arm
 a^{10} causing its cushioned end a^{31} to contact
with the piano action so that the hammer b^1
will strike the harp string b . Since the atmos-
pheric pressure above the diaphragm a^{20} is
equal to the pressure in chamber a^{34} below the
diaphragm a^{20} after air is admitted to this
latter chamber, the air in the chamber a^{32}
is greater than atmospheric pressure and
consequently raises the stem a^4 and its at-
tendant parts, causing the stem to push
against the felt a^{24} and button a^8 raising the
striking rocker arm a^{10} . As soon as this per-
foration in the music sheet has passed the
duct in the tracker bar and the blank paper
takes its place, then tendency to vacuum
created thru the channel d^5 again asserts
itself and the diaphragm a^{15} falls, the air
having been bled off thru the opening
 a^{30} , passage a^{40} , passage a^{41} and passage
 a^{42} , channel d^5 , tube d^2 and bellows d^1 , caus-
ing a^{17} to seat. At the same time vacuum is
created in passages a^{48} , a^{49} , a^{50} , passage a^{47} ,
passage a^{46} , passages a^{46} and a^{44} and cham-
bers a^{34} and a^{33} , the air having been bled off
thru a^{52} allowing striking rocker arm
 a^{10} to fall along with plunger a^4 and its con-
nections upon the downward movement of
diaphragms a^5 and a^{20} . It will be understood
that there is at all times maintained a partial
vacuum in a^{32} while the piano player action is
in operation.

It can readily be seen from the description
that with very little labor and knowledge
of such mechanism, any of the striker units
may be removed and replaced without the
usual taking apart of other contiguous units,
or whole tiers of units, or their connections.
This improvement not only embodies a pro-
nounced decrease in cost of repairing and re-
placing parts but makes possible the carrying
as a standard part the striker unit a duplicate
of which may be procured and used to replace
a defective one.

As the power diaphragms a^5 are protected
from dust and dirt and enclosed so that they
are not continuously in free contact with the
air, their effective life is very greatly in-
creased, and much expense and trouble saved
thereby.

I do not wish to be limited to the precise
structure shown and described for many
changes may be made in the mechanism with-
out departing from the spirit of my inven-
tion, and I claim as within the scope of my
invention all forms readable on the claims.

I claim as my invention and desire to se-

cure by Letters Patent of the United States:

1. In combination with an air line having
pressure and relief sides; pneumatic actuating
means for musical instruments comprising
a casing, two openings in said casing, one
for connecting said casing with the pressure
side and another for connecting said casing
with the relief side of said air line, an unitary
means for producing pressure for the entire
musical instrument, a chamber within said
casing, a main power diaphragm disposed
substantially horizontally across said cham-
ber, means for admitting external air under
said diaphragm to raise it whenever the
vacuum in said air line is broken, a plunger
adapted to rest upon said diaphragm and to
be actuated by it and power transmitting
means outside said casing adapted to be actu-
ated by said plunger.

2. For use in a player piano action having
an unitary pressure producing mechanism, a
separate striker unit for each note, said unit
comprising a casing having chambers di-
rectly connected with the main air channel
and with the air conduit connected with the
tracker bar, and having a main power dia-
phragm and a valve operating diaphragm
both substantially horizontally disposed
within said chambers formed in said casing,
conduit means within said casing for con-
necting the tracker bar conduit with said
valve operating diaphragm chamber, said
valve controlling ports to external air, said
ports, and conduit means within said cas-
ing for connecting the main air channel with
the main diaphragm chamber above said dia-
phragm for exhausting air therefrom, con-
duit means within said casing for connecting
the valve diaphragm chamber above its dia-
phragm with the main air channel for ex-
hausting air therefrom, conduit means for
conveying external air from said ports to
the power diaphragm chamber below said
diaphragm to force said diaphragm upward-
ly, and means operated by said main dia-
phragm for actuating power transmitting
means located outside of said casing.

3. For use in connection with a player
piano action having an air line with pressure
and relief sides, unitary means for producing
pressure, a main air channel on the pressure
side of said air line and a tracker bar, a
complete and separate striker unit for each
note, each said unit comprising a rigid cas-
ing directly connected with the main air
channel and the air conduit connected with
the tracker bar, a chamber within said cas-
ing, a main power diaphragm disposed sub-
stantially horizontally across said chamber,
a plunger actuated by said main power dia-
phragm, power transmitting means actuated
by said plunger, a second chamber within
said casing, a diaphragm disposed substan-
tially horizontally across said second cham-
ber, a valve opened by the raising of said

second diaphragm, ports opening conduits within said casing to external air upon the raising of said valve, said conduits connecting said ports with the chamber under said main power diaphragm, conduits connecting the main air channel with the chamber above said main power diaphragm and also with the chamber above said valve operating diaphragm, means for connecting the tracker-bar air conduit with the chamber under said valve operating diaphragm so that a partial vacuum will constantly be maintained in the chambers above both said diaphragms.

4. Pneumatic actuating means for the mechanical player mechanism of a musical instrument having an unitary pressure producing mechanism, comprising a casing for a striker unit, an opening in said casing directly connected with the vacuum channel of the player mechanism, another opening in said casing connected with the tracker-bar of said player mechanism, an air port through the casing of said mechanism to admit external air directly thereinto, a valve to control the admission of air into said casing through said port upon admission of air to said casing thru said inlet connected with the tracker-bar, a plunger to transmit power from said unit to other parts of the player mechanism, means for actuating said plunger, air passages to connect said port with said actuating means, and connections from said vacuum opening to said valve-actuating and plunger-actuating means to facilitate an unbalancing of pressures therein when air is admitted thereto.

5. Pneumatic actuating means for the mechanical player mechanism of a musical instrument having an unitary pressure producing mechanism, comprising a casing for a striker unit, an opening in said casing directly connected with the vacuum channel of the player mechanism, another opening in said casing connected with the tracker bar of said mechanism, an air port thru the casing of said mechanism to admit external air directly thereinto, a valve to control the admission of air into said casing thru said port, a chamber, a diaphragm in said chamber to actuate said valve upon admission of air to said chamber under said diaphragm thru said inlet connected with the tracker bar, a plunger to transmit power, a second chamber, a diaphragm in said second chamber for actuating said plunger, air passages to connect said port with the chamber under said diaphragm, connections from said vacuum opening to the chambers above said diaphragms actuating said valve and plunger to facilitate an unbalancing of pressures in the chambers in which said diaphragms are mounted when air is admitted to said chambers on the opposite sides of said diaphragms and means for bleeding away the air from

the pressure sides of said diaphragms thru the vacuum opening of said casing.

6. In a striker unit for the mechanical player mechanism of a musical instrument having an unitary pressure producing mechanism, the combination of a casing for said unit, a plunger to operate the power transmitting means, a diaphragm to actuate said plunger, an air port thru the casing of said unit, a valve to control the admission of air into said casing thru said port, and connections from said port to the underside of said diaphragm to supply air thereto to actuate it.

7. In combination with a musical instrument having striking mechanism, a gas line with pressure and relief sides, and a unitary means for producing said pressure; separate actuating mechanisms for each note of said instrument, each of said actuating mechanisms formed as a completely encased removable unit, comprising a rigid casing for said mechanism, a chamber within said casing, a main power diaphragm disposed across said chamber, means for causing said diaphragm to be raised by combined vacuum and gas pressure, a plunger actuated by said diaphragm and power transmitting means outside said casing adapted to be actuated by said plunger to operate the striking mechanism for one note, a connection from each actuating mechanism to the pressure side of said gas line, and a connection from each actuating mechanism to the relief side of said gas line.

8. In combination with a musical instrument having a striking mechanism, an air line with pressure and relief sides, a main air channel on the pressure side, an air conduit on the relief side and an unitary means for producing said pressure; a rigid casing directly connected with said main air channel, means for connecting said casing with the air conduit, a chamber within said casing, a main power diaphragm disposed across said chamber, means for causing said diaphragm to be raised by combined vacuum and air pressure, a plunger actuated by said diaphragm and power transmitting means outside said casing adapted to be actuated by said plunger.

9. In combination with the player mechanism of a player piano, including a tracker bar, an air line with pressure and relief sides, and an unitary means for producing pressure for the entire mechanism; actuating mechanism comprising a rigid removable casing, a chamber within said casing, a main power diaphragm disposed across said chamber, air chambers and passages within said casing and means for controlling the flow of air therethrough, so that air pressure will be applied below and vacuum created above said diaphragm to raise it, a plunger actuated by said diaphragm and power transmit-

ting means outside said casing adapted to be actuated by said plunger.

10. In combination with a player mechanism of a player piano, including a tracker bar, an air line with pressure and relief sides, and an unitary means for producing pressure for the entire mechanism; actuating means comprising a rigid removable casing, a connection from said casing to the pressure side of said air line, a connection from said casing to the relief side of said air line, a chamber formed within said casing, a main power diaphragm disposed substantially horizontally across said chamber, means within said 15 casing for causing said main power diaphragm to be raised by combined vacuum above and air pressure below said diaphragm, a plunger actuated by said diaphragm, power transmitting means pivoted to the outside of 20 said casing and adapted to be actuated by said plunger, and a second diaphragm above the first to which said plunger is secured, and means for supplying air pressure to the underside of said second diaphragm.

25. 11. A player piano action having in combination, a tracker bar, an air conduit connected at one end to said tracker bar, a self contained note producing unit for each note connected to said air conduit and comprising, 30 a rigid casing, a small air chamber connected to said air conduit, a main air chamber and a plurality of air passages within said casing, apertures through said casing into said air passages, a plunger valve normally closing said apertures and a flexible diaphragm in said small chamber actuating said plunger and valve, a striking rocker arm pivotally connected to said casing, a strike plunger secured to said arm and 35 extending through said casing into said main air chamber, a diaphragm horizontally disposed across said chamber actuating said strike plunger, a single bellows for all said note producing units and air connections, 40 from said bellows to said units.

45. 12. In combination with the player action of a piano, an unitary self contained note producing means for each note, comprising a casing all the walls of which are immovably 50 fixed, a main air chamber and an auxiliary air chamber within said casing, interrelated air passages within said casing, apertures through said casing into said passages, a plunger valve normally closing said apertures, a diaphragm in said auxiliary chamber actuating said plunger valve, a striking rocker arm pivotally fixed to said casing, a strike plunger secured to said arm and extending through said casing into said main 55 air chamber and a diaphragm in said main air chamber actuating said strike plunger.

60. In testimony whereof I have hereunto set my hand.
